US00D874444S

(12) **United States Design Patent** (10) **Patent No.:** **US D874,444 S**
Chang et al. (45) **Date of Patent:** **** Feb. 4, 2020**

(54) **HEADSET**

(71) Applicant: **Quanta Computer Inc.**, Taoyuan (TW)

(72) Inventors: **Jung-Wen Chang**, Taoyuan (TW);
Kao-Yu Hsu, Taoyuan (TW)

(73) Assignee: **QUANTA COMPUTER INC.**,
Guishan Dist., Taoyuan (TW)

(**) Term: **15 Years**

(21) Appl. No.: **29/660,083**

(22) Filed: **Aug. 17, 2018**

(30) **Foreign Application Priority Data**

Jul. 5, 2018 (TW) 107303831

(51) **LOC (12) Cl.** **14-01**

(52) **U.S. Cl.**

USPC **D14/223**

(57) **CLAIM**

The ornamental design for a headset, as shown and described.

DESCRIPTION

FIG. 1 is a perspective view of a headset, showing our new and ornamental design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings depict environment that form no part of the claimed design.

1 Claim, 7 Drawing Sheets
